UNITED STATES PATENT OFFICE

RENEE THORNTON, OF NEW YORK, N. Y.

DESIGN FOR A BOX COVER

Application filed October 5, 1929. Serial No. 32,957. Term of patent 14 years.

To all whom it may concern:

Be it known that I, RENEE THORNTON, a citizen of the United States, residing at New York, in the county and State of New York, have invented a new, original, and ornamental Design for a Box Cover, of which the following is a specification, reference being had to the accompanying drawing, forming a part thereof.

I claim:

The ornamental design for a box cover as shown.

RENEE THORNTON.
